METHOD AND APPARATUS FOR PROVIDING A CONTROLLED SUPPLY OF SULPHUR COMBUSTION GASES

John B. Chatelain and Gordon A. Cain, Freeport, Tex., assignors to Freeport Sulphur Company, New York, N. Y., a corporation of Delaware

Application June 7, 1939, Serial No. 277,908

6 Claims. (Cl. 23—278)

This invention relates to new and improved apparatuses and methods for providing a controlled supply of sulphur combustion gases, more particularly, sulphur dioxide in comparatively small quantities.

In the burning of sulphur for the commercial production of sulphur dioxide, we have observed that the quantity and the consistency of the combustion gases are affected by a number of variables. These variables are primarily: (1) the physical state and temperature of the sulphur; (2) the depth of the sulphur in the combustion chamber; (3) the cross-sectional area of the burning surface; (4) the rate of heat radiation from the combustion chamber, and (5) the amount of combustion supporting gases supplied. The relative importance of each of these variables becomes greater as the quantity of combustion gases required becomes less, the range within which they must be controlled becomes narrower, and the demand for consistency in them becomes higher.

Many sulphur burners and methods of burning sulphur have heretofore been described that will operate satisfactorily if the rate at which sulphur is to be burned is comparatively high and variable amounts of combustion products of high consistency are not demanded. However, the operation of conventional burners at rates wherein sulphur is burned in comparatively small portions within narrow limits, is attended with great difficulty of control, requiring constant supervision to maintain the burning rates within such limits. Furthermore, it is generally recognized that the operation of various conventional types of sulphur burners at very low burning rates is accomplished by the likelihood of cessation of combustion and interruption of continuous operation.

Although sulphur dioxide gases and particularly its solutions in water have applications in industrial processes, its use in many of these processes requiring only very small, continuous but variable and accurately controlled amounts of sulphur dioxide has been limited due to the cost of providing compressed, or liquid sulphur dioxide, or cost of supplying the necessary additional equipment to control accurately the feeding thereof. The cost of such equipment and the supervision required to produce sulphur dioxide by burning sulphur at accurately controlled and easily varied rates has heretofore proven prohibitive. The latter is peculiarly true in operations which require the use of sulphur dioxide under pressure. For instance, according to past practices, it has often proven impractical to use

sulphur dioxide in many flocculation, reduction, bleaching and acid imparting and alkalinity reducing processes because of the cost of the raw materials and equipment necessary.

5 It is an object of the present invention to provide processes and apparatuses for supplying a controlled supply of sulphur combustion gases at rates which will make the use of said combustion gases commercially feasible in processes heretofore found unprofitable. A further purpose of 10 this invention is to provide a method and an apparatus for burning sulphur at variable rates to produce sulphur dioxide of high consistency in easily controllable quantities.

More particularly the object of this invention is to provide a method and apparatus for burning sulphur continuously at relatively low rates under complete control to produce sulphur dioxide in variable amounts exactly in the quantities desired.

20 In obtaining these objectives, the number of variable factors affecting the rate of the burning of sulphur, are in accordance with the present invention, reduced to a minimum such that the amount and consistency of the combustion gases produced are easily controlled by regulation of the remaining variable quantities. Constancy is obtained primarily by providing a supply of liquid sulphur in such relation to the combustion chamber and with such connections that the sulphur is caused to flow into the combustion chamber at a point below the surface of the burning sulphur without agitating this surface and in accordance with a control system which is automatically responsive to the level of the sulphur in the combustion chamber. With the arrangement of apparatus hereinafter described, the amount of sulphur combustion gases produced under ordinary circumstances will vary in direct proportion to the amount of combustion supporting gases introduced into the combustion chamber. When the amount of combustion gases to be produced is extremely small and the requirements more exacting, the quantity and the consistency of the combustion gases can be further modified by controlling the rate of heat loss from the combustion chamber as will hereinafter be more fully described.

40 The preferred construction and features of our invention will be made apparent by the following detailed descriptions of several illustrative embodiments of the invention when considered in conjunction with the accompanying drawings.

50 In the drawings, Fig. 1 is a view in vertical section of a typical embodiment of the invention.

The apparatus shown in Fig. 2, in vertical section, illustrates a second embodiment provided with means for maintaining the temperature of the sulphur supply constant and in the molten condition.

The apparatus shown in Fig. 3, likewise in vertical section, illustrates a third embodiment provided with a cone-shaped combustion chamber whereby the surface area of the sulphur in such chamber can be altered by varying the depth of the sulphur therein.

In Fig. 1, there is shown a combustion chamber 10 having an inlet 11 for the combustion supporting gases provided with a control valve 12, an outlet 13 for the combustion gases provided with an auxiliary ejector 14. A sulphur supply source 15 is connected to a liquid sulphur supply container 16 through a valve 17, the container 16 being connected to the combustion chamber 10 through a conduit 18 terminating near the bottom of the chamber or below the level of the sulphur to be maintained therein and a conduit 19 terminating at a higher point in the chamber or at the level of the sulphur, the conduit 18 having a valve 20. The combustion chamber 10 is also provided with a sealable hand hole 21 for gaining access to the interior of the burner and a plate or baffle 25 serving as a distributor and deflector for the combustion supporting gases.

In Fig. 2, wherein the same numbers are used to represent corresponding parts, the sulphur supply source 15 and the supply container 16 are surrounded by a heating jacket 25 connected by a conduit 26 having a control damper 27 therein and a conduit 28 to the combustion gas outlet 13a containing a control damper 29. The combustion chamber 10 may be enclosed in a jacket 30 for steam or other heating or cooling gases.

In Fig. 3, wherein the same numbers are used, the conduit 18 is connected with a conduit 19a having therein a screw threaded adjustable stem 35 connected to a movable extension conduit 36 for varying the depth of the liquid in the conical shaped combustion chamber 10a. A scale 37 and pointer 38 are provided in connection with the stem 35 to indicate the height of the liquid in the combustion chamber and its surface area.

In starting the operation of the equipment, the burner or combustion chamber 10 or 10a is filled to a level below the end of conduit 19 or 36 with either solid or molten sulphur by introducing the same through the hand hole 21, or from the supply source 15 through the valve 17, the supply container 16 and the conduit 18. When the sulphur has reached the proper level in the burner 10, the supply container 16 is filled with molten sulphur from the supply source 15. The sulphur is lighted by means of a match introduced through the handhole 21. A draught is created through the burner by forcing air or other gaseous medium through the auxiliary conduit 14. When the flame has spread over the entire area of the sulphur hand hole 21 is closed, air is supplied through the inlet 11, and the air pressure in conduit 14 is cut out of operation. The combustion supporting gases may be supplied through inlet 11 by an adjustable blower or any other suitable device.

When combustion has reached a desirable stage, valve 20 is opened, valve 17 being kept closed. A part of the liquid sulphur in the container 16 will then flow through the conduit 18 and enter the burner at a point near its bottom, the sulphur continuing to flow into the burner

as long as air or gas can enter the conduit 19 and pass up the conduit 18 to the container 16, or until the level of the pool of molten sulphur reaches the level of the opening of the conduit 19.

Automatic operation of the system is obtained by reason of the fact that a partial vacuum is created in the container 16 and, as the sulphur is burned in the combustion chamber 10 and 10 the level of the sulphur is lowered below the opening of conduit 19, air enters and permits sulphur to flow to the burner until the level rises to a point which stops the ingress of air. The level of liquid sulphur in the burner hence 15 will remain constant or not vary more than a very small fraction of an inch.

When the supply of sulphur in the container 16 is near exhaustion the valve 20 is closed and the valve 17 is opened to admit more sulphur 20 from the supply hopper 15. Although no sulphur will be fed to the combustion chamber 10 during the period when the valve 20 is closed, the container 16 can be filled so quickly that the level of the sulphur in the burner 10 is 25 sufficiently affected to produce any appreciable variation in the burning rate of the sulphur. During the filling of the container 16 with molten sulphur, the air therein easily escapes through the valve 17 and through the molten 30 sulphur of the supply source 15 into the atmosphere above, thereby allowing a free flow of the molten sulphur into the container 16. When the container 16 has become filled with sulphur, valve 17 is closed and valve 20 is opened, thereby 35 again putting into operation the automatic feeding and constant control mechanism.

Since the sulphur in the supply chamber 15 and that in the container 16 must be melted and maintained in such a condition, some external 40 heating means must be employed. This heat can be supplied by providing a steam jacket, or by windings of suitable electric heating wire or by any other convenient means, such as by causing the hot combustion gases which leave the burner 45 10 through the outlet conduit 13a to pass through a jacket 25 surrounding the container 16 and the hopper 15 as illustrated in Fig. 2 of the drawings. Dampers 27 and 29 in conduit 26 and in the outlet 13a respectively may be used to control the 50 amount of combustion gases which are diverted and caused to pass through the jacket 25. By regulating the position of the dampers 27 and 29, the temperature in the supply source 15 and the container 16 is controlled.

In Fig. 2 the burner 10 is shown surrounded by a jacket 30 which permits an even more finite control of the quality of the combustion gases produced, especially when small portions of sulphur are being burned at a slow rate, by controlling the rate of heat loss from the combustion 60 chamber.

The dimensions of the combustion chamber 10 may vary within wide limits depending upon the rate of sulphur burning desired and the rate of 65 production of combustion gases demanded. With respect to the size of the container 16, it is preferable that it hold a sufficient volume of sulphur to permit operation of the apparatus for a whole day without replenishment.

Fig. 3 illustrates a modification of the invention containing in addition to the means for control of the previously described embodiments a further control means enabling the operator to vary the surface area of the burning sulphur. 70 The combustion chamber 10a is an inverted cone

presenting a different horizontal cross-sectional area at every different level, the level of the sulphur therein being controlled at will by the operator through raising or lowering of the conduit 36. The same results may be obtained by a pyramid or any other similar figure having a variable horizontal cross-sectional area.

The apparatus of each of the embodiments hereinbefore described provides a constant supply of liquid sulphur to the combustion chamber at a distance below the surface of the burning sulphur which does not disturb such surface. Therefore three of the hereinbefore enumerated variables affecting the rate of burning and the consistency of sulphur combustion gases are automatically controlled. That is to say, the apparatus herein described makes possible a process whereby sulphur is provided continuously in the molten state to a mass of burning sulphur which not only has a constant depth in the combustion chamber but also has a constant area of burning surface. The combustion space above the burning surface is also constant. Only two variables, namely the rate of heat loss from the combustion chamber and the rate of supply of combustion supporting gases, are left to be controlled. Of these two remaining variables the amount of heat loss from the surface of the combustion chamber is of relatively much less importance. Therefore, a constant supply of combustion supporting gases will provide a constant amount of sulphur combustion gases of satisfactory consistency. Wide variation in the amount of such gases produced may be had by merely varying the amount of combustion supporting gases supplied.

In the operation of apparatus of Fig. 3, the most satisfactory surface area desirable for providing the amount or rate of supply of sulphur combustion gases needed can be preliminarily determined.

The apparatus of this invention has been found to supply sulphur dioxide of satisfactory consistency over a range of 40% to 200% of the rated capacity of the sulphur burner, merely by varying the volume of the combustion supporting gases.

Only when it is desirable to produce very small quantities of sulphur combustion gases within very narrow limits and of high consistency is it desirable to control the amount of heat loss from the combustion chamber. Such controls are sometimes necessary where the rate of sulphur burning is not more than one pound per hour. This loss of heat may be controlled by any suitable means of heat insulation or heat control.

It is sometimes desirable, however, to control the amount of heat radiation when the burner is being operated at a rate greatly in excess of its normal capacity. In this instance it is necessary to increase the rate of heat loss from the combustion chamber which may be done by using cool blasts of air, by water jackets, by sprays or by other known methods.

Through a correlation of the amount of combustion supporting gases and the rate of heat loss, it is possible to produce sulphur combustion gases of very high consistency at any predetermined rate. Small variations in the rate of production of sulphur combustion gases may be procured by maintaining the supply of combustion supporting gases constant and varying the rate of heat loss.

The process and apparatus of the instant invention takes into account the traces of oil which

develop in the burning of sulphur and form a scum or a film on the burning surface. This film becomes relatively constant after the combustion has progressed for a short period of time, for in the instant apparatus, the surface is not disturbed by the sulphur replenishing operation, the sulphur being slowly fed into the burner at a point below the burning surface.

An advantage of the apparatus of the invention 10 is that it can be operated under either atmospheric or superatmospheric pressures. Since the sulphur supply container is sealed, the differentiation between the pressure above the liquid in the supply container and that at the surface of the burning liquid is the same regardless of the pressure conditions existing in the combustion chamber. This advantageous operation would not be possible if the source of supply of the liquid sulphur were exposed to the atmosphere.

For instance, consider a burner operated under 15 atmospheric pressure of 14.7 pounds per square inch with the height of the sulphur in the supply container 4 feet above the level of the sulphur in the combustion chamber. When the sulphur is at this level, the vacuum holding up the column 20 of sulphur is 4×0.8 or 3.2 pounds per square inch gauge, the pressure of one foot of molten sulphur being figured at 0.8 pound per square inch. Actually a pressure of 14.7-3.2 or 11.5 exists in the 25 space above the level of the surface. If the level of the sulphur in the supply container were to fall to 3 feet above the level of sulphur in the combustion chamber, the vacuum holding up the column of sulphur is equal to 3×0.8 or 2.4 pounds per square inch gauge. This principle will 30 continue to operate until all the sulphur is fed from the sulphur container.

Assuming the same state of facts, except that the operating pressure is 25 pounds per square 35 inch, then the pressure above the column when at the four-foot level will be 25-3.2 or 21.8 pounds per square inch, but the pressure above the liquid in the combustion chamber is 25 pounds per square inch, and the differential remains the same as heretofore. Therefore the functioning of the apparatus is independent of the pressure conditions. Naturally the same principles would operate if the pressure were sub-atmospheric.

Various attachments may be added to increase the efficiency or convenience of operation of the apparatus of the present invention. For instance, the applicants have found that just the right amount of sulphur dioxide needed for treating liquid or other materials can be obtained by using a metering device which regulates the supply of combustion supporting gases in direct proportion to the volume of liquid or other material being treated. The metering device is built up on the basis of experimentation and a plotting of curves showing just the amount of combustion gases needed to supply the desired sulphur dioxide for the varying amounts of materials being treated.

The simplicity, ease of control, and the inexpensiveness of the burners and processes of this invention and their adaptability to the productions of small quantities of sulphur dioxide of high consistency makes them useful in many fields where prior known processes and apparatuses have proven too expensive, too complex, or even inoperative. Such fields of use include, for instance, supplying sulphur dioxide to boiler water to form alkaline sulphites thereby reducing the alkalinity of the liquid in the boiler and at the same time providing alkaline sulphites for the

removal of dissolved oxygen and alkaline sulphates for the proper maintenance of the sulphate-carbonate ratio in the boiler water. Sulphur dioxide produced by our process can likewise be utilized in treatment of municipal water for reducing the pH of such water to the point of optimum flocculation for various coagulants, thereby effecting more efficient removal of coloring and suspended matter while employing lower doses of coagulants. The sulphur dioxide can also be used in municipal water treatment as an anti-chlor or as a decolorizer. The use of sulphur dioxide as a decolorizing and bleaching agent in the manufacture of sugar and a bleaching agent for certain textiles is likewise made easier. The ready availability of sulphur dioxide produced in accordance with the processes of this invention makes its use, in many instances, preferable to the use of acids such as sulphuric acid, because its employment involves less danger and the product is much more easily handled. The provision of sulphur dioxide under pressure in easily controlled amounts makes the use of the process advantageous in any instance where the production of sulphites and/or sulphates is desired.

The example will serve to show the general principles of operation and will show the constancy with which a burner will operate.

Example 1

A burner of the type described having a burning surface of 1.1 square feet burned an average of 1.78 pounds of sulphur per hour for a period of 77 hours. During this entire period the air supplied the burner remained constant at 7 cubic feet per minute. The maximum burning rate recorded during this period was 1.83 pounds per hour with the minimum being 1.59 pounds per hour. The temperature of the combustion gases leaving the burner varied from a minimum of 375° F. to a maximum of 390° F. The level controller maintained a level that varied a maximum of one-sixteenth inch from the average during a one month period of operation.

In another burner it was found that a variation in the supply of air from 10 cubic feet per minute to 40 cubic feet per minute resulted in a sulphur consumption varying directly with the supply of air and ranging between about 3.1 to 6.15 pounds per hour. The variation in sulphur consumption per unit of time was as small as in the above example.

From the foregoing example and illustrative embodiment of the invention it is readily seen that it is possible to vary the rate at which the sulphur is burned by merely varying the rate at which air is supplied to the burner. If it is desirable to regulate the rate of sulphur dioxide production in direct proportion to another process variable, such as the volume of the substance being treated with sulphur dioxide, this can be done by providing satisfactory metering equipment which will automatically change the rate at which air is supplied the burner as the volume of the material which is receiving sulphur dioxide treatment varies. Such a method makes it possible to produce sulphur dioxide at a variable rate, accurately controlled within narrow limits in an automatic manner, the only manual operation required being the daily filling of the molten sulphur supply container.

It should be understood that the present invention is not limited to the specific process, reactive conditions, and apparatus disclosed

herein but that it extends to all equivalents which one skilled in the art would consider within the general purport of the instant disclosure as limited only by the tenor of the specification and the requirements of the appended claims.

We claim:

1. In an apparatus for providing a controlled supply of sulphur combustion gases, a combustion chamber having an inlet for combustion supporting gases and an outlet for combustion gases, a closed liquid sulphur supply container positioned at a higher level than that of said combustion chamber, a sulphur supply conduit connected with said supply container and terminating in the combustion chamber, a conduit branching from the said supply conduit and terminating in said combustion chamber at a level above the terminal of said supply conduit, valve means adapted to stop passage of fluids in said conduits between the sulphur supply container and the combustion chamber when the sulphur supply container is opened to the atmosphere for refilling.
2. In the production of sulphur combustion gases, the method of providing a constant supply of such gases from a burning surface of a liquid body of sulphur in a combustion chamber which comprises, supplying liquid sulphur to the body of burning sulphur at the rate the sulphur is consumed in said chamber by maintaining a column of liquid sulphur contiguous with and at a higher level than that of the body of sulphur in the combustion chamber, said column being retained by differences in gaseous pressure upon the surfaces of the column and the body of liquid, and in response to the lowering of the level of the liquid sulphur in the combustion chamber due to combustion of sulphur, admitting sulphur from said column to restore the level in said chamber by increasing the gaseous pressure upon the surface of the liquid in the column.
3. In the production of sulphur combustion gases, the method of providing a constant supply of such gases from a burning surface of a liquid body of sulphur in a combustion chamber which comprises, supplying liquid sulphur to the body of burning sulphur at the rate the sulphur is consumed in said chamber by maintaining under partial vacuum a column of liquid sulphur contiguous with and at a higher level than that of the body of the sulphur in the combustion chamber and in response to the lowering of the level of sulphur in said combustion chamber as sulphur therein is consumed, introducing gas into the partial vacuum in a quantity which permits sufficient sulphur to restore the surface level thereof in the combustion chamber.
4. In an apparatus for providing a controlled supply of sulphur combustion gases, a combustion chamber having an inlet for combustion supporting gases and an outlet for combustion gases, a closed supply container positioned for gravitational flow of sulphur into said combustion chamber, a liquid-sulphur supply conduit connected to said supply container and terminating in the combustion chamber, and a second conduit connected to said container terminating in the combustion chamber at a point above the terminal of said supply conduit, said conduits having valve means for stopping the passage of fluids therethrough when the sulphur supply container is opened to the atmosphere for refilling.

5. In an apparatus for burning sulphur and controlling the supply of combustion gases, a combustion chamber having a variable horizontal cross-sectional area and having an inlet for air and an outlet for combustion gases, a closed liquid sulphur supply container positioned for gravitational flow of sulphur into said combustion chamber, a conduit connected to said container and terminating in said combustion chamber, a second conduit connected to said container and terminating at a point above the first mentioned conduit and having means for varying the level of its terminal, said conduits being provided with valve means for discontinuing the flow of fluids between said supply container and said combustion chamber.

6. In an apparatus for providing a controlled supply of sulphur combustion gases, a combus-

tion chamber having an inlet for combustion supporting gases and an outlet for combustion gases, a closed liquid sulphur supply container positioned at a higher level than that of said combustion chamber, a conduit connected to said supply container and terminating in the combustion chamber at a point below the desired surface level for burning sulphur, a second conduit connected to said supply container and having its lower extremity positioned at a level above that of the first conduit, a supply tank positioned above said supply container connected therewith, said supply container and supply tank being surrounded by a jacket connected with said outlet for combustion gases.
